(57) **CLAIM**

I claim the ornamental design for a headset, as shown and described.

DESCRIPTION

FIG. 1 is a top plan view of a headset showing my new design, the cord in all views is drawn broken away to show indeterminate length;

FIG. 2 is a left side view thereof;

FIG. 3 is a front view thereof;

FIG. 4 is a right side view thereof;

FIG. 5 is a bottom plan view thereof;

FIG. 6 is a perspective front view thereof;

FIG. 7 is a perspective rear view thereof; and,

FIG. 8 is a rear view thereof.
